F. S. CARVER

PLATEN FOR POT PRESSES

Filed March 23, 1925

FIG. 1. INVENTOR
Fred S. Carver

BY H. H. Dyke
ATTORNEY

Patented Jan. 19, 1926.

1,570,433

UNITED STATES PATENT OFFICE.

FRED S. CARVER, OF EAST ORANGE, NEW JERSEY.

PLATEN FOR POT PRESSES.

Application filed March 23, 1925. Serial No. 17,602.

To all whom it may concern:

Be it known that I, FRED S. CARVER, a citizen of the United States, and a resident of East Orange, Essex County, and State of New Jersey, have invented a new and useful Improvement in Platens for Pot Presses, of which the following is a specification.

My invention relates to platens for pot presses, and particularly to the provision of platens therefor which are readily removable from the press without dismantling.

It has heretofore been necessary to dismantle pot presses in order to remove the platens, as when platens are broken or required to be repaired. Such a press is shown in my prior Patent No. 1,478,699 of Dec. 25, 1923. Presses of this type having platens mounted on steps, as, for example, the steps 24 shown in my said prior patent, require all the platens to be different in construction in that the consecutive platens are constructed with lugs for supporting them on their step supports, which lugs are of increasingly greater length from the bottom platen to the top platen of the press, so that when the platens are dropped down after the pressing operation is performed, each will be stopped at its own normal location in the press. This has involved the making of as many kinds of platens for each press as there are platens in the press. Platens so differently constructed for the different locations in the press are not interchangeable and in case of a replacement, for example, of a broken platen, only a platen of the same construction and adapted for the particular location in the press can be made use of. A further and very considerable disadvantage in such prior presses is that removal of a platen can be accomplished only by dismantling the press, including the removal of the supporting racks, and, in presses of certain makes, requiring the removal of the presshead and other major structural parts of the press, all of which must be reassembled and in some cases the press practically rebuilt after the platen is replaced.

The principal object of the present invention is the doing away with the necessity for dismantling of the structural parts of the press, such as racks, columns, presshead and the like, in order to permit removal or replacement of one or more of the press platens. Another object of the invention consists in so constructing the platens as to

make same interchangeable. Another object consists in the provision of separate stop lugs for these interchangeable platens, which serve to adapt the otherwise interchangeable platens for their individual locations in the press. Another object consists in the provision of means whereby the stop lugs which are preferably screwed in the platens may be screwed out while the platen is in the press, which in turn permits the respective platens to be dropped down from their respective steps without removal of the supporting racks, and whereby the platens can be gotten into such position as to be tipped up and withdrawn or introduced between the columns and racks of the press without disturbing or dismantling either the columns or racks.

In the accompanying drawings, I have shown sufficient portions of the pot press to illustrate the application to such presses of the present invention and in said drawings Fig. 1 is a partial side view of a pot press, such as shown in greater detail in Fig. 1 of my said prior patent, with parts broken away for disclosing the interior construction and with the runway members or platen slides removed from the platens. Fig. 2 is a fragmentary view, the same as a portion of Fig. 1, but showing one of the platens raised off its step and one of its screw stop lugs screwed out. Figs. 1 and 2 are taken approximately along the line 2—2 of Fig. 4 and looking in the direction of the arrows. Fig. 3 is a horizontal sectional view on the line 3—3, Fig. 1. Fig. 4 is a fragmentary view taken approximately along the line 4—4, Fig. 3, showing the lowermost of three platens in normal position, the uppermost thereof raised and the intermediate platen lowered down on one side and raised on the other side to permit withdrawal of the last named platen between the columns and racks, which remain in place. Fig. 5 is a detail view of a screw stop lug.

In said drawings, the combined press base and cylinder 10 and the presshead 12 are connected by the columns 14. The racks 16 in which the press pots (not shown) slide in and out are secured to the base and head, preferably two on each side of the press.

These racks 16 are provided with the steps 18 which extend inwardly toward one another by uniformly increasingly greater distances from the top to the bottom of the

press in order that each platen may be stopped upon being dropped down after pressing by its respective stop. The construction thus far described is as shown in 5 my said prior patent.

A novel feature of the racks 16 of the present invention is that same are cut back or recessed between the steps 18 as shown at 20 to provide room for screwing out the 10 screw stop lugs hereinafter referred to.

The platens are designated by reference numeral 22. Instead of constructing same unlike and with integral stop lugs of different lengths as heretofore, the platens are all 15 made alike and interchangeable, whereby they are adapted to be finish machined all alike in a gang or stack and manufacture is facilitated. Platens 22 are provided with bosses 23 at their corners. Said bosses have 20 each a screw threaded hole 24 formed therein for the reception of the screw stop lugs 26.

Stop lugs 26 are preferably constructed substantially as shown in detail in Fig. 5, comprising the lug portion 28 with the reduced threaded stud portion 30 having the 25 threads cut away adjacent to the shoulder 32 so that when the lug 26 is screwed into the threaded hole 24 in the platen boss it shoulders home to a lock joint. The lugs 26 30 are screwed out and in by means of a drift pin inserted in the holes 34 bored preferably at right angles to one another through the lug portions 28. The lug portions 28 of stop lugs 26 for the respective platens are 35 made of suitably differing lengths to adapt the respective platens for being stopped by their respective steps, as clearly shown in Fig. 2.

The columns 12 serve as guides for the up 40 and down movement of platens 22 and the bored corners of platens 22 which run on the guide columns 12 are bored eccentrically as indicated at 40, Fig. 3, so as to make 45 practically close contact with the columns in the short inter-column direction and to have a moderately substantial clearance away from the columns on the line of the relatively long inter-column direction. (See Fig. 4.) This clearance is sufficient to establish such relation between the platens 50 and columns that when the platens are otherwise free to tip they can be tipped in the direction of the longer inter-column dimension without making contact with and binding between the columns. This eccentricity and capacity for tippability of the platens does not interfere with their being accurately guided by the columns when so tipped. One of the platens 22 is shown in 55 Fig. 4 after having been tipped free from the columns in this manner.

In order to remove the platen after the runways or platen slides (not shown) are removed from the platen and one or more 60 pots taken out for working convenience, the

platens to be removed is made accessible by raising the platen or platens located thereabove, whereupon the particular platen to be removed is raised somewhat as shown in Fig. 2 to bring the screw stop lug 26 thereof 70 opposite the recess 20 in the rack 16. The screw stop lugs can now be screwed out as indicated in the case of the right hand lug in the middle platen shown in Fig. 2. It is usually sufficient to unscrew two of the lugs on one of the ends of the platen, preferably those of the end it is desired to be dropped or tipped down. When this is done the platen can be dropped down at this end past its step and raised at the other end 75 and made to assume substantially the position shown in Fig. 4. (It will be noted that the pot runways 42 in the racks 16 are cleared by the platen. See Fig. 3.) With the platen in tipped position as indicated in Fig. 4 same can be drawn out between the racks 16 while in such tipped position, without disturbing or dismantling either the racks or columns. This operation is reversed in case of insertion of the platen. 80

I claim:

1. In a pot press having stops for stopping the platens at their individual stations, a series of platens provided with separable stop lugs of length to adapt the platens to be stopped by their respective steps. 95
2. The combination with a platen for pot presses of screwed in lugs adapted to support the platen by resting on steps of a supporting rack forming a part of the press, said racks being recessed to permit unscrewing the lugs without disturbing the racks. 100
3. A pot press having steps of successively increasing length for stopping the respective pot platens in their downward movement and comprising columns serving as guides for the up and down movement of the platens, said platens having column engaging portions eccentrically related to the column, whereby the platens can be tipped with respect to the column and still be guided correctly by the column in the up and down sliding movement, and separable lugs for supporting the platens on their individual steps. 105
4. In a pot press, platen guiding means, platens guided thereby and adapted to be tipped with respect to the guiding means, and separable stop means on said platens. 110
5. In a pot press comprising base, head and connecting columns and racks, the racks being provided with platen steps, platens guided by the columns, and separable stop means on the platens, said stop means adapted to extend from the various platens a sufficient distance to engage the respective steps. 115
6. A platen for a pot press comprising separable supporting lugs. 120
7. A platen for a pot press comprising 125

screw supporting lugs screwed into the platen.

8. The method of making platens for pot presses adapted to be stopped by steps of varying extent of projection, which includes making all the platens alike and of formation adapted to pass by all the steps of the

press, and separably securing thereto stop members adapted to extend sufficiently beyond the platen to engage the step for the respective platen. 10

In testimony whereof, I have signed my name hereto.

FRED S. CARVER.
